UNITED STATES PATENT OFFICE.

WILLIAM MERKER, OF NEW YORK, N. Y.

COMBINATION CUSHIONED FLAT AND FILLER.

1,079,789.

Specification of Letters Patent. Patented Nov. 25, 1913.

Application filed December 28, 1912. Serial No. 739,067.

To all whom it may concern:

Be it known that I, WILLIAM MERKER, a citizen of the United States, and a resident of the city of New York, borough of 5 Brooklyn, in the county of Kings and State of New York, have invented a new and Improved Combination Cushioned Flat and Filler, of which the following is a full, clear, and exact description.

10 The invention relates to egg carriers provided with foldable or collapsible fillers formed of interlocked strips providing individual cells for the eggs, and its object is to provide a new and improved cushioned 15 flat and filler arranged to reduce breakage of the eggs while in the egg carrier to a minimum and to protect the members forming the filler from being bent or broken, thus insuring long life of the egg carrier 20 and permitting its re-use for a long period.

In order to accomplish the desired result use is made of cushions mounted on the flat for the eggs to rest on, and interlocking strips of cardboard or similar material and 25 forming cells each having one of the said cushions at the bottom, the interlocking strips running in one direction being provided at the top edges with reinforcing 30 bindings of metal or the like, and the interlocking strips running in the opposite direction being provided at the bottom with reinforcing bindings.

A practical embodiment of the invention is represented in the accompanying drawings 35 forming a part of this specification, in which similar characters of reference indicate corresponding parts in all the views.

Figure 1 is a sectional side elevation of an egg carrier provided with the improved 40 cushioned flat and filler; Fig. 2 is a plan view of part of the same; and Fig. 3 is an enlarged sectional perspective view of part of the combination cushioned flat and filler.

The cushioned flat A and the filler B for 45 providing individual cells for the eggs are arranged in tiers in a crate or box C of the usual construction. The flat A formed of cardboard or other suitable material is provided on its upper face with cushions in the 50 form of platforms D made of cardboard or other material, each platform being provided at opposite sides with integral arms D' inclined inwardly and downwardly and terminating at their lower ends in integral 55 outwardly-extending flanges D², pasted, glued or otherwise fastened to the upper

face of the flat A. It is understood that a cushion is provided at each cell formed by the filler B so that each egg rests on a platform D, and as the latter is free to yield the 60 egg is not liable to be broken while the egg carrier containing the eggs is in transit.

The filler B is formed of the usual intersecting, longitudinal and transverse strips B' and B² of cardboard or other suitable 65 material, and interlocked with each other in the usual manner by providing the strip B' at the intersections with the strip B² with slots B³ extending from the bottom upward, and by providing the strip B² at the intersection with the strip B' with slots B⁴ extending from the top downward. By the arrangement described the upper edges of the strips B' are continuous from one end to the other, and the said upper edges are 70 bound and reinforced by bindings E, preferably in the form of U-shaped metallic bars extending the entire length of the said upper edges of the strips B'. In a like manner the lower and bottom edges of the strips B² are 75 continuous and are bound and reinforced by bindings E' and extend the entire length of the said lower edges of the strips B². By the arrangement described the bindings E' 80 rest on the upper surface of the bottom flat A while the next flat A for the following tier rests on the bindings E of the strips B', and the terminals of the metallic bindings E, E' abut against the sides and ends of the 85 box C so that the strips B' and B² are not liable to be injured especially at the ends thereof. By reinforcing the strips B' and B² of the filler B the latter is rendered 90 exceedingly strong and durable and the upper strips E form a firm support for the flat A 95 of the next tier above.

By reference to the drawings it will be noticed that the cushions D are approximately square when viewed in plane and spaced apart and the cushions are arranged in longitudinal and transverse rows spaced apart to form intersecting grooves for the reception of the lower edges of the strips B' and B² of the filler whereby the filler is practically centered on the flat and held against collapsing, and each cell contains a single cushion D for an egg to rest on.

By reference to Figs. 1 and 3, it will be noticed that the bottom edges of the strips B' are practically free or spaced from the bottom flat A, while the upper edges of the strips B² are below the top edges of the bind-

ings E, and hence the member below the next following flat A and the other unprotected portions of the strips B' and B² are not liable to be injured when the fillers are 5 in use in the crate or box C. By this construction also ventilating openings are formed at the top and bottom of each of the fillers.

From the foregoing it will be seen that a 10 cushion is provided for each cell and each filler has its strips protected to insure long life of the filler and permitting its re-use for a long period. It is understood that the filler when not in use can be folded flat in the 15 usual manner.

Having thus described my invention, I claim as new and desire to secure by Letters Patent:

An egg carrier having a plurality of cells 20 formed by longitudinal and transverse strips, the strips extending in one direction

having their upper edges bound with U-shaped metallic bars and provided with slots extending from the bottom upwardly, and the strips extending in the other direction 25 having their lower edges bound with similar bars and provided with slots extending from the top downwardly; the sets of strips being interlocked, with the binding bars of the strips of one set at the top and the binding bars of the strips of the other set at the bottom, the binding bars of one set projecting beyond the unbound edges of the other set.

In testimony whereof I have signed my 35 name to the specification in the presence of two subscribing witnesses.

WILLIAM MERKER.
